CLAIM

The ornamental design for a housing for a head-mounted display as shown and described.

DESCRIPTION

FIG. 1 is a front perspective view of a housing for a head-mounted display, showing a new design;

FIG. 2 is a front view of the housing of FIG. 1;

FIG. 3 is a rear view of the housing of FIG. 1;

FIG. 4 is a left side view of the housing of FIG. 1;

FIG. 5 is a right side view of the housing of FIG. 1;

FIG. 6 is a top view of the housing of FIG. 1;

FIG. 7 is a bottom view of the housing of FIG. 1; and,

FIG. 8 is a bottom perspective view of the housing of FIG. 1.

The broken lines are for the purpose of illustrating portions of the housing for head-mounted displays that form no part of the claimed design.
